UNITED STATES PATENT OFFICE.

ERNEST P. CAMPBELL, OF STOCKTON, CALIFORNIA.

BEARING PULLER.

Application filed May 4, 1921. Serial No. 466,803.

To all whom it may concern:

Be it known that I, ERNEST P. CAMPBELL, a citizen of the United States, residing at Stockton, county of San Joaquin, State of California, have invented certain new and useful Improvements in Bearing Pullers; and I do declare the following to be a full, clear, and exact description of the same, reference being had to the accompanying drawings, and to the characters of reference marked thereon, which form a part of this application.

This invention relates to improvements in bearing pullers such as are used to draw the inner races of ball bearings from the shafts on which they are driven, and is particularly an improvement over that type of puller shown in my Patent No. 1,171,590, dated February 15th, 1916.

The principal object of the present invention is to construct a puller of the above mentioned type in such a manner that the jaws are inter-changeable. This feature alone marks a great improvement over the former type, since it means that when the devices are being manufactured the jaws are all made exact duplicates of each other and when assembling the pullers, the jaws may be taken up at random, instead of having to have a certain one to cooperate with the adjacent one, as was the case with the puller already patented. Both operations above cited means reduced costs in manufacturing.

This inter-changeability of the jaws also permits the ready replacement of a jaw from a stock assortment on hand or sent from the factory.

Another object of this invention is to arrange that the screw-pin, which is forced against the shaft when pulling a bearing, shall have a considerable and constant bearing area for its threads, irrespective of the spreading of the jaws. This feature is also lacking in the previously mentioned patented article.

As a whole, the article has been made more efficient, while the cost of manufacture has been reduced.

The above objects I accomplish by means of such structure and relative arrangement of parts as will fully appear by a perusal of the following specification and claims.

In the drawings similar characters of reference indicate corresponding parts in the several views.

Fig. 1 is a side elevation of the puller.

Fig. 2 is a sectional elevation thereof.

Fig. 3 is a fragmentary section through the screw-collar.

Referring now more particularly to the characters of reference on the drawings the numeral 1 denotes a threaded pin provided at one end with a turning handle 2 and at the other with a tapered point 3 to engage the usual socket in the end of a shaft 4 having the bearing 5 thereon to be pulled.

Threaded on the pin is a sleeve 6 having a central outwardly projecting flange 7. Surrounding the sleeve and extending lengthwise of the pin in the direction away from the handle are jaws 8 provided at one end with grooves 9 to engage the flange 7 and at the other with flanges or lugs 10 projecting inwardly and shaped to fit the groove 11 in the bearing.

Surrounding the jaws loosely is a collar 12, threaded into which are screws 13, one for each jaw, and which pass through said jaws and seat in orifices 14 in the sleeve-flange 7. The sleeve 6 tapers inwardly somewhat toward each end from the flange 7, so as to allow freedom of movement of the jaws. The screws also pass freely through the jaws so as not to cause a binding of any of such parts.

At the opposite ends of the jaws the latter are enlarged and taper outwardly somewhat toward such end, as shown at 15, and are surrounded by a taper-bored ring or collar 16, which may be retracted onto the smaller portion of the jaws to allow the latter to be spread, to engage a bearing, and may then be moved onto and wedged firmly in contact with the tapered portion, so as to clamp the jaws with the bearing.

In practice, two of such rings would be supplied with one of the pullers, in order to accommodate one size of the device to a greater variety of bearing sizes.

In order to normally hold the jaws spread apart, a band spring 17 is mounted under the sleeve 6 to bear against the inner periphery of the jaws.

It will be seen from the foregoing description that the chief difference between this device and the one shown in the aforementioned patent is in the manner of connecting the jaws to the operating or pulling screw so that the screw at all times has a constant area of engagement with the sleeve,

while at the same time the jaws are allowed plenty of flexibility of movement at their outer ends.

Also it will be noted that the jaws not being threaded, they may all be jiggled to a common standard, and hence are interchangeable.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not for a departure from the spirit of the invention, as defined by the appended claims.

Having thus described my invention, what I claim as new and useful and desire to secure by Letters Patent is:

1. A bearing puller comprising a threaded pin adapted for rotation, a sleeve threaded onto the pin, an outwardly projecting flange on said sleeve, and a plurality of bearing-engaging jaws surrounding said sleeve and provided with grooves in which said flange seats and being flexibly connected thereto. 25

2. A bearing puller comprising a threaded pin adapted for rotation, a sleeve threaded onto the pin, an outwardly projecting flange on said sleeve, a plurality of jaws surrounding said sleeve and provided with grooves in which said flange seats, a collar surrounding the jaws in the plane of the flange, and screws threaded into the collar and passing 30 freely through the jaws and being seated in the flange. 35

In testimony whereof I affix my signature.

ERNEST P. CAMPBELL.
